Primary Examiner — Dominic V Simone(74) *Attorney, Agent, or Firm* — Banner & Witcoff, Ltd.**(57) CLAIM**

The ornamental design for a shoe, as shown and described.

DESCRIPTION

FIG. 1 is a rear perspective view of a shoe showing my new design;

FIG. 2 is a second rear perspective view thereof;

FIG. 3 is a front perspective view thereof;

FIG. 4 is a second front perspective view thereof;

FIG. 5 is a side view thereof;

FIG. 6 is an opposite side view thereof; and,

FIG. 7 is a rear view thereof.

The even-length broken lines within the shaded area represent stitching and form no part of the claimed design. The uneven-length broken lines immediately adjacent to the shaded area define the bounds of the claimed design and form no part thereof. The uneven-length broken lines depicting the remainder of the shoe show features that form no part of the claimed design.
